ABSTRACT OF THE DISCLOSURE

In an electrofluid-dynamic generator an elongated corona discharge electrode is positioned adjacent an elongated attractor electrode with a channel provided between. The ends of the corona discharge electrode and the attractor electrode are shaped to form an expansion nozzle adjacent the edge of the corona discharge electrode. A collector electrode is spaced from the corona discharge and attractor electrodes in line with the nozzle. A shield electrode is provided between the nozzle and the collector electrode. A high pressure, high temperature gas is directed through the nozzle toward the collector electrode. An electric field is established between the corona discharge electrode and attractor electrode. The gas after passing the collector electrode is recirculated past the corona discharge and attractor electrodes to provide a low pressure region adjacent a portion of the corona discharge electrode shielded from the high pressure gases within the nozzle to aid in the establishment of a corona discharge from the corona discharge electrode. The recirculated gas also aids in keeping the charge particles in the main stream from reaching insulators provided between the shield electrode and the collector electrode and also permits the use of an increased width in the conversion section which in turn allows an increased length in the conversion section and therefore a corresponding higher voltage.

BACKGROUND OF THE INVENTION

The electrofluid-dynamic process makes use of non-conducting gas to transport unipolar charges directly against the action of an electrostatic field. In this process charged particles of one polarity are transported by fluid-dynamic energy from the grounded entrance electrode to the collector electrode against the electrostatic field which is generated by the electrical potential of the collector electrode.

In the electrofluid-dynamic energy conversion process, the efficiency, the power output of a generator of a given size, depends on the ratio of the total charge on the charged particles to the mass of the carrier fluid, in the energy conversion section between the two electrodes, that is substantially on the space charge density. The limitation on the space charge density is the dielectric strength of the working fluid and in actual practice the maximum field strength can be in the neighborhood of one half the dielectric strength. With the conveyor gas, carrying the space charge, passing through a cylindrical conversion section as shown in FIG. 1A, neglecting end effects, the maximum field strength due to space charge occurs next to the surface of the section, and is proportional to the space charge in a given length of the section divided by the surface area of the same length. Therefore by increasing the surface area of the conversion section, the total space charge in the conversion section can be increased without dielectric breakdown. This can be accomplished by providing a beam which is elongated in one dimension to form a rectangular-shaped beam as shown in FIG. 1B. Other configurations can be used

2

which will provide an increased surface area for a given cross-sectional area of the beam, for example, an annular beam configuration or a radial beam configuration.

SUMMARY OF THE INVENTION

According to this invention, use is made of an elongated beam configuration to provide a larger charge to mass ratio and thus provide a greater efficiency. A corona discharge is provided between an elongated knife-edge electrode which is shaped and positioned to provide an elongated divergent nozzle adjacent the knife-edge electrode. A high temperature, high pressure gaseous material such as steam or mercury vapor is supplied to the divergent nozzle so that a portion of the gaseous material is condensed around the charged particles to provide droplets of the order of $\frac{1}{100}$ micron diameter or larger to provide a greater drag interaction force between the charges and the gaseous flow such that there is negligible slip between the charged droplets and the flow. A portion of the knife-edge electrode is shielded from the high pressure gas to more readily permit the establishment of the corona discharge. A secondary flow path is directed into the conversion channel to restrict the beam flow and to provide a greater volume flow of working medium which results in greater electrical power extraction. The shielded portion of the knife-edge electrode lies in the secondary flow which is at a lower pressure.

BRIEF DESCRIPTION OF THE DRAWING

FIG. 1A is a diagrammatic illustration showing the cross section of the gas stream in prior art devices;

FIG. 1B is a diagrammatic illustration showing one possible gas stream cross section according to this invention;

FIG. 2 is a cross-sectional view of an electrofluid-dynamic generator according to one embodiment of the invention;

FIG. 3 is an enlarged cross-sectional view of the nozzle structure for the device of FIG. 2;

FIG. 4 is a diagrammatic view partially in section of an electrofluid-dynamic structure according to another embodiment of the invention;

FIG. 5 is an enlarged cross-sectional view of a portion of one of the units of the device of FIG. 4;

FIG. 6 is a reduced top plan view of one of the collector divergent channel forming structures of the device of FIG. 5; and

FIG. 7 is an enlarged sectional view of the nozzle structure for the device of FIG. 5.

50 DETAILED DESCRIPTION OF THE INVENTION

Reference is now made to FIG. 2 of the drawing, which shows an electrofluid-dynamic energy conversion system 10 having an annular knife-edge electrode 11 and an annular attractor electrode 13 with an annular channel 14 therebetween. As shown in FIG. 3, the tip of the knife-edge electrode projects toward the attractor electrode and forms together therewith a divergent nozzle 15 as indicated by the different length lines L_1 and L_2 . A high temperature, high pressure gaseous material such as steam or mercury vapor at between 20 and 400 atmospheres and at a temperature, selected in the manner as will be explained later, is supplied to the nozzle 15 through channel 14, supply inlet 16 and an annular channel 18. Knife-edge electrode 11 is insulated from the attractor electrode 13 by means of annular insulators 20 and 21. O-rings 22 provide a pressure seal for the gaseous material in channel 18. A plurality of bolts 25, two of which are shown, secure the knife-edge electrode 11 to the attractor electrode 13 and are insulated from the attractor electrode by insulators 27.

Collector electrode structure 29 is positioned downstream of the nozzle 15. A shield electrode 30 having an electrical connector 31 is positioned between the connector electrode structure 29 and the nozzle 15. The shield electrode 30 has inner and outer annular members 32 and 32' electrically interconnected by a plurality of connector members 34, one of which is shown. The shield electrode member 32 is electrically connected to the attractor electrode 13 by means of a plurality of connectors 34', one of which is shown. The desired electrical potential is applied to the corona discharge electrode 11 by means of leader 28. The collector electrode structure is supported on the shield structure 30 by means of annular insulators 33 and 33'. The anode structure has annular conical members 35 and 36 which form a passage 37 divergent in the direction of the flow. An end member 40 is secured to the conical member 36 and acts to direct a secondary flow of gaseous material between cylindrical elements 42 and 43 back through passages 45 and 46 past the knife-edge electrode 11 and attractor electrode 13. Structures 35 and 40 are interconnected by means of a plurality of spaced connectors 38, one of which is shown. Output electrode 39 is connected to end member 40. The conical elements 35 and 36 are supported on insulators 33 and 33' by means of annular support members 49 and 50, respectively. The width of the conversion section is limited by a pair of annular insulators 52 and 53 supported on support members 49 and 50, respectively. Since gaseous material is continually being supplied through the nozzle, an outlet 55 is provided in the housing 56 to bleed off an amount of gaseous material equal to that supplied through nozzle 15. Though not shown, the gaseous material from outlet 55 could be returned to the gaseous material supply.

Other arrangements for this device may be used, for example, other annular streams could be positioned radially outward and surrounding the stream shown. Also arrangements could be used wherein attractor electrodes are positioned on both sides of the corona discharge electrode or needle electrodes may be placed on each side of an attractor electrode.

In the operation of the device, a high temperature, high pressure gas is supplied to nozzle 15 through supply inlet 16 and annular channels 18 and 14. Thus gas flows from nozzle 15 through passage 37, back between elements 42 and 43 to provide a secondary flow through passages 45 and 46 adjacent the knife-edge electrode and attractor electrode, respectively. The secondary flow mixes with the main flow from nozzle 15 between the nozzle and the conversion section and in the conversion section between insulators 52 and 53.

The desired potential is established between the knife-edge electrode 11 and the attractor electrode 13 to establish a corona discharge between the knife-edge electrode and the attractor electrode. Since the portion of the knife-edge electrode 11', shown in FIG. 3, is in the lower pressure secondary stream, a corona discharge is readily established in this region of the knife-edge electrode. Except when a gas such as air is used, the flow of gaseous material in the divergent nozzle 15 causes a portion of the gaseous material to condense around the charged particles which are then carried to the collector electrode structure by drag interaction force. Because the charged particles are carried away by the high velocity gaseous material, substantially no charge reaches the attractor electrode so that the attractor current is substantially zero. Any condensed material is returned to the gaseous phase in the expansion passage 37 so that substantially dry gas flows through passages 45 and 46. The temperature of the inlet gaseous material is selected to provide substantially dry gaseous flow in the passages 45 and 46 and will be determined by various factors such as the geometry and materials used in the apparatus.

A device that is more compact and easier to construct than the device described is shown in FIG. 4. In this de-

vice, the collector electrode structure 59 is positioned in the center of a cylindrical chamber. Annular nozzle structure 61 surrounds the collector structure and directs a gaseous stream radially inwardly toward the collector structure. With this arrangement, a plurality of electrofluid-dynamic units can be located within a single cylindrical enclosure 63 with the collector structure 59 being supported between insulators 65 and 66 with the collector lead 67 passing out through one of the insulators. Since all of the fluid dynamic units are identical, one of these units will be described with respect to FIGS. 5, 6 and 7.

The nozzle structure shown in greater detail in FIG. 7 has an annular knife-edge electrode 70 and an attractor electrode 71 forming an annular passage 74 and nozzle 75. An inlet 77 feeds an annular channel 78 which supplies gaseous material to annular passage 74. Insulating spacers 80 and 81 with O-ring seals 82 are provided between the knife-edge electrode 70 and attractor electrode 71. The knife-edge electrode is secured to the attractor electrode by means of a plurality of bolts 85, one of which is shown. Bolt 85 is insulated from knife-edge electrode by insulator 87. Lead 89 is connected to knife-edge electrode for applying the desired potential thereto. The attractor electrode may be connected at ground potential through the gas supply inlet 77 as shown or may be connected to the shield electrode 90, made up of two annular members 90a and 90b, which are connected at ground potential by means of a plurality of annularly spaced support connectors 93. The gas stream from the nozzle is directed toward the centrally positioned individual collector structures 60 which make up the overall collector structure 59. Each of the collector structures 60 has a pair of circular members 95 and 96 which are shaped to form a divergent passage 98 each having a web center support member 99 as shown in FIG. 6. The web support member 99 are positioned and supported between collector flow directors 101. The conversion section passage width is limited by annular insulators 103 and 104 secured to annular screen members 90a and 90b and members 95 and 96, respectively. A secondary flow path 108 is provided between the units with secondary flow passages 109 and 110 provided adjacent the nozzle 75. The operation of this device is substantially the same as that of the device of FIG. 2.

Various materials may be used in these devices for example the metal parts can be stainless steel and the insulators can be ceramic material. Also though a pressure range of 20 to 400 atmospheres has been described, it is to be understood that higher pressures may be used to advantage if apparatus is built to withstand the higher pressures.

There is thus provided an electrofluid-dynamic conversion system which provides greater efficiency than prior art devices.

While certain specific embodiments have been described in detail, it is obvious that numerous changes may be made without departing from the general principles and scope of the invention.

I claim:

1. An electrofluid-dynamic energy conversion system comprising: an elongated nozzle; means for supplying a flow of high pressure gaseous material through said nozzle; said nozzle being formed by a knife-edge electrode, elongated in a direction perpendicular to the direction of flow, on one side of the gaseous flow and a second electrode, elongated in a direction perpendicular to the direction of flow, on the other side of the gaseous flow; means, including said knife-edge electrode and said second elongated electrode means, for providing a corona discharge into the flow within said nozzle; a collector electrode spaced from said nozzle; and output means connected to said collector electrode.

2. The device as recited in claim 1 including means for providing a secondary flow of gaseous material of a lower pressure than said high pressure gaseous material past both

sides of said nozzle.

3. The device as recited in claim 2 wherein said elongated knife-edge electrode and said second electrode are annular electrodes forming an annular divergent nozzle.

4. The device as recited in claim 3 wherein said nozzle surrounds said collector electrode and said nozzle provides a radial stream directed inwardly toward said collector electrode.

5. The device as recited in claim 3 wherein an annular shielding electrode is positioned between the nozzle and the collector electrode.

6. The device as recited in claim 5 wherein said nozzle surrounds said collector electrode and said nozzle provides a radial stream directed inwardly toward said collector electrode.

7. The device as recited in claim 5 wherein said gaseous material is a high pressure vapor.

8. The device as recited in claim 7 wherein said nozzle surrounds said collector electrode and said nozzle provides a radial stream directed inwardly toward said collector electrode.
